SUN SCREEN

John J. Grebe, Midland, and Walkley B. Ewing,
Grand Rapids, Mich., assignors to Ewing De-
velopment Company, Bay City, Mich., a corpo-
ration of Michigan

Application January 13, 1941, Serial No. 374,194

16 Claims.

(Cl. 154—46)

This invention relates to an improved sun-screen. In a preferred embodiment it concerns a sun-screen formed by slitting and folding sheet material.

An object of the invention is to provide a sun-screen of the Venetian blind type which, without adjustment, will be effective in excluding the direct rays of the sun both when the sun is at a high altitude and an azimuthal angle roughly normal to the shade and when the sun is nearly on the horizon and at an oblique angle to the screen, and which at the same time will permit materially greater vision directly through the screen than do most conventional shades.

Another object is to provide a screen which can be readily and inexpensively fabricated by simple operations from a single piece of sheet material.

These and other objects are accomplished in the sun-screen of the invention, which consists essentially of a plurality of parallel strips of sheet material spaced at intervals not greatly exceeding the width of a strip, and spaced parallel legs of sheet material inclined to the general plane of the screen and connecting the strips at intervals along the lengths thereof, as herein-after described with reference to the accompanying drawings, in which

Figure 1 is an enlarged front elevation of a small portion of a preferred form of the sun-screen according to the invention;

Figure 2 is a cross-section along the line 2—2 of Figure 1;

Figure 3 is an enlarged plan view of a portion of slit blank used in making the screen of Figures 1 and 2;

Figure 4 is an enlarged perspective view showing the blank of Figure 3 partially expanded into the screen of Figures 1 and 2; and

Figure 5 is an enlarged perspective view of another form of screen according to the invention.

The sun-screen illustrated in Figures 1 and 2 is formed by slitting and folding a single sheet of material, as will be explained, and consists of a series of parallel strips 6 of elongated cross-section which are vertically superposed at equal intervals not greatly exceeding, and preferably approximately equal to, the width of a strip, and are inclined, preferably at least 45°, to the general plane of the screen, i. e. to the vertical. As shown, each individual strip 6 extends horizontally across the screen and lies in a single plane, and is offset regularly in the same direction at equal intervals along its length, as at 7, the distance of offset not exceeding about three-fourths

the width of the strip, and being advantageously about one-half such width. The strips 6 are joined together by vertical rows of legs 8 formed of sheet material integral with that of the strips, each leg having a width substantially equal to the regular offset distance of each strip, i. e. not greater than about three-fourths the width of a strip, and connecting a front portion 9 of a strip with the corresponding oppositely offset rear edge 10 of an adjacent strip. The rows of legs 8 are ordinarily spaced apart a distance large in comparison to the intervals between adjacent strips. As will be seen from the drawings, the legs 8 are inclined to the general plane of the screen, and are also rather sharply inclined to the strips to which they are attached. The legs in any given row are ordinarily in the same or in parallel vertical planes, and preferably have their centers all in the same vertical line, in order to give a generally rectangular appearance to the screen.

While the sun-screen is illustrated with only two offsets per strip and two rows of legs, it will be appreciated that it may comprise any number of offsets and corresponding rows of legs, to form a screen of the desired dimensions. In general, the width of a strip will be from one-eighth to one-half inch, and the distance between rows of legs one-half to five inches, although other sizes are equally possible. The screen is usually fabricated of thin sheet metal, but may also be formed of other flexible, strong materials, such as synthetic plastic sheet.

In making the sun-screen illustrated, the sheet material is first slit to form a blank, as in Figure 3, which is then formed into the screen. In the slit blank, which is preferably rhomboidal in shape to avoid waste, the slits are all substantially parallel to one another, and are disposed on the bias to an edge of the sheet, the bias angle 11 being determined as hereinafter explained. As shown, the slits are arranged in a plurality of like parallel series, as at 12 and 12'. The individual lines within a series are regularly offset a distance which does not exceed about three-fourths the distance between corresponding lines of adjacent series, and overlap at their offset positions a distance which does not greatly exceed, and need not equal, the distance between corresponding lines of adjacent series. As a result of this slitting, there are formed parallel continuous regularly offset strip members 6 interconnected at their corresponding oppositely offset portions by leg members 8.

55 The blank slit as described is formed into

sun-screen by successively displacing each strip member 6 by accurately controlled means, in a direction diagonally downward and backward substantially in the bias direction, i. e. parallel to the long edge of the strip, thus forcing the strips into vertically superposed parallel planes, and causing the leg members 8 to become sharply inclined to the strips and to the general plane of the screen. A partially folded blank showing two of the strip members already displaced into position is illustrated in Figure 4. The displacement of the strip members 6, and the concurrent formation of the legs 8, may be rendered more accurate by defining on the blank fold lines 13 to mark the point of juncture of the leg members 8 with the strips 6, either by suitably crimping the blank or by other means. The fold lines 13 are ordinarily oblique to the long edges of the strips 6 (as at angle 11' in Fig. 3) and are preferably in the same or parallel planes.

The angle at which the strips 6 are inclined to the general plane of the screen is controlled primarily by the angle 11' of the fold lines, and to a lesser extent by the bias angle 11. In making the screen, these angles and the various dimensions of the strips 6 and leg members 8 are chosen so that, in the final screen, the strips 6 have an inclination capable of providing the desired protection from direct sunlight. The precise choice of these angles and dimensions is made from mathematical formulas which have been developed from the geometry of the screen and the blank.

In use, the sun-screen is ordinarily mounted in a frame or hung in such manner that the strips are inclined down and outwardly toward the direction of the sun, and that the strips 6 are horizontal. For eastern and western exposures, where the rays of the sun are for the most part at an acute angle to the plane of the screen, the screen is also mounted so that the legs 8 face toward the sun. Thus, if the screen in Figure 1 is considered as viewed from outside a window being shaded, it is in position for use in a westerly exposure, the sun being to the right, or south. For an east window, the screen would be inverted, i. e. top for bottom and inside for out, so that the legs face to the left. Likewise, for certain exposures where it is necessary, seasonal or even diurnal changes in the general direction of incidence of the sun's rays on the screen may be met by inverting the screen, thus affording protection at all times.

The unusual and advantageous characteristics imparted to the sun-screen of the invention by its regularly offset strips 6 and interconnecting leg members 8 may best be understood from the following considerations:

The number of hours during the day in which a shading device of the Venetian blind type affords complete shade against the direct rays of the sun is relatively small. Now, from the geometry of such a device, it will be evident that, for such devices at most windows, the period of complete shade may be prolonged materially either (a) by rotating the whole shade, in the plane of the window, to bring the sun more nearly into a plane normal to the face of the shade and parallel to the vertical center line thereof, e. g. by slanting all the strips downwardly from one end to the other, or (b) by rotating the whole shade about its vertical center line in that direction which will decrease the angle of incidence of the sun's rays on the shade, e. g. by pushing one side of the shade out of the window. 75

Purely for prolonging the period of complete shade, and without regard to practicability, either or both of these rotations are preferable to the conventional practice of adjusting the strips 6 of the shade to a sharper tilt, since, unlike the latter, they do not reduce the open area of the shade, and hence do not restrict outward vision or exclude ingress of reflected light. Of course, with existing shading devices, the rotations described would be so obviously awkward and difficult as to be impractical.

In the sun-screen of the present invention, however, the structure is divided into many small units in which advantage is taken of both the shade-prolonging rotations discussed, and yet the structure as a whole remains in the plane of the shaded opening and rectangular to it in general pattern and appearance. Thus, as will be evident from Figure 1, in any strip 6, each individual element lying between any two legs 8 is rotated slightly in the general plane of the screen, being inclined downwardly from left to right. However, because of the regular offset members 7, which exactly make up for this downward slant, the entire strip 6, constituting a series of individual strip elements which extend from one end of the screen to the other, presents a strictly horizontal appearance. Again, each individual element extends from left to right outwardly from the plane of the screen, but the offset members in the strip make up for this extension, so that the screen as a whole is substantially in a single plane.

While the use of regularly offset strips as described tends toward a longer period of complete shade because of the two rotations of the individual shading elements, it will also be evident that if strips were merely thus offset without further structural provision, material leakage of sunlight would occur through the screen at the gaps left at each offset position. In the screen of the invention, however, the leg members 8 extend fully from the offset at the edge of one strip to the corresponding opposite offset on the adjacent strip, and thus precisely fill the gap in the shade which would otherwise be present. In other words, the presence of leg members 8 at each offset of each strip not only contributes to the structural unity of the screen, but also is functional to the shading purpose of the screen.

Another screen structure according to the invention which retains the advantageous characteristics just discussed is shown in Figure 5. This latter screen consists of a series of parallel strips 6 which are substantially identical with the strips as in Figures 1 and 2. However, in the screen of Figure 5, the legs 14 interconnecting the strips 6 at their offset positions are formed of sheet material which is vertically continuous, and are provided at equal intervals with slots 15 into which the strips 6 fit. In a slight variation of this structure, the strips need not be horizontally continuous, but may be made up of individual elements secured to the legs and offset regularly, to give a structure substantially identical with that of Figure 5.

The sun-screen of the invention, particularly in the preferred embodiment of Figures 1 and 2, possesses a number of advantages other than the efficiency of exclusion of oblique rays of the sun already mentioned. The screen may be fabricated by extremely simple means from a single sheet of material, and can be made in any desired size. The metal in the screen is not under stress,

having been merely folded into position. The structure presents only smooth, flat surfaces, and hence collects little dust or dirt, and can be easily cleaned. If desired, it may be rolled up for shipping.

A number of minor variations of the sun-screen are possible without departing from the invention. Thus, the screen may be formed of sheet material which is a dark color on the top but reflective on the bottom, so that the direct rays of the sun are absorbed and do not penetrate the screen, but cooler reflected light from the near ground is reflected inwardly. If desired, the screen may be fabricated of a sheet composed of two materials of different coefficients of expansion, such as a bimetallic laminated sheet; in this case the angle of inclination of the strips in the finished screen will automatically vary with temperature changes, thus permitting the rays of the sun to pass through the screen to a greater degree when it is cool than when it is hot. Corrugated strips may be provided by using corrugated sheet in making the screen or impressing corrugations in the forming operation, thereby giving added strength to the final screen. Again, the screen may be reinforced vertically, as by rolling or soldering vertical wires into the screen at the offset corners of the strips, or may be edged with a continuous tape or selvage edge secured to or integral with the material forming the individual strips. Such an edge, which is easily made in the plane of the screen during the forming operation, can readily be anchored to frames of any type, and can be rolled or crimped to form seams which permit ready joining of two or more screens to produce a wider structure. These and other variations within the scope of the claims will doubtless occur to those skilled in the art.

It is to be understood that the foregoing description is illustrative rather than strictly limitative, and that the invention is coextensive in scope with the following claims.

We claim:

1. In a sun-screen, a plurality of parallel strips of sheet material inclined to the general plane of the screen and spaced at intervals not greatly exceeding the width of a strip, and spaced parallel legs of sheet material inclined to the general plane of the screen and connecting the strips at intervals along the lengths thereof.

2. In a sunscreen, a plurality of parallel strips of sheet material inclined to the general plane of the screen and spaced apart at intervals approximately equal to the width of a strip, and spaced parallel legs of sheet material inclined to the general plane of the screen and connecting the strips at intervals along the lengths thereof.

3. A screen according to claim 2 wherein the strips are inclined to the plane of the screen at an angle of at least 45°.

4. A screen according to claim 2 wherein the legs are arranged in vertical rows, all the legs in each row being in substantially the same vertical plane.

5. In a sun-screen, a plurality of parallel strips of sheet material inclined to the general plane of the screen and spaced at equal intervals not greatly exceeding the width of a strip, and spaced parallel legs of sheet material integral with that of the strips inclined to the plane of the sun-screen and to the strips, and connecting the front portion of each strip with the rear portion of an adjacent strip at intervals along the length there- 75

of, the width of a leg not exceeding about three-fourths the width of a strip.

6. In a sun-screen, a series of parallel vertically superposed horizontally extending series of strip elements, the individual elements of each horizontal series being inclined to the general plane of the screen and to the horizontal and being interconnected in offset relation, and leg members connecting the strip elements of each horizontal series with the corresponding elements of an adjacent horizontal series.

7. In a sunscreen, a plurality of parallel vertically superposed horizontally extending series of strip elements, the individual elements of each horizontal series being inclined to the general plane of the screen and to the horizontal and being interconnected by offset members, the elements and offset members of each horizontal series together constituting a single integral strip lying in one plane, and leg members connecting the strip elements of each horizontal series with the corresponding elements of an adjacent horizontal series.

8. A sunscreen according to claim 7 wherein the horizontally extending series of strip elements are vertically superposed at equal distances approximately equal to the width of a strip element, and wherein the individual strip elements are inclined to the general plane of the screen at an angle of at least 45°.

9. In a sun-screen, a series of parallel horizontally disposed strip members which extend across the screen and are offset at intervals along their lengths and are vertically superposed at intervals not greatly exceeding the width of a strip, and legs of sheet material interconnecting the strips at intervals along their lengths.

10. In a sun-screen, a series of parallel inclined strips vertically superposed at equal intervals not greatly exceeding the width of a strip, each strip extending horizontally across the screen in a single plane and being offset at regular intervals along its length, and legs of sheet material inclined to the general plane of the screen and interconnecting the strips at the offsets thereof.

11. In a sun-screen, a series of parallel strips of sheet material vertically superposed at equal intervals not greatly exceeding the width of a strip, each strip being inclined to the general plane of the screen and extending horizontally across the screen in a single plane, and being offset at regular intervals along its length a fixed distance not exceeding about three-fourths the widths of a strip, and legs inclined to the plane of the screen and formed of sheet material integral with that of the strips and connecting the offset portions of each strip with the corresponding oppositely offset portions of the adjacent strips.

12. A sun-screen formed by slitting and folding sheet material and comprising a series of parallel strips vertically superposed at equal intervals not greatly exceeding the width of a strip, each strip being inclined at least 45° to the general plane of the screen and extending horizontally across the screen in a single plane, and being regularly offset at equal intervals along its length a fixed distance not exceeding three-fourths the width of a strip, and vertical rows of legs formed of sheet material integral with that of the strips, each leg being inclined to the plane of the screen and having a width substantially equal to the offset distance of the strips and connecting an offset portion of a strip with

the corresponding oppositely offset portion of an adjacent strip.

13. A shade screen according to claim 12 wherein the interval between adjacent strips is approximately equal to the width of a strip.

14. A blank capable of being formed into a sun-screen comprising a sheet substantially rhomboidal in shape having therein on the bias to an edge thereof a plurality of series of parallel regularly offset overlapping slits, said slitted sheet thus defining a plurality of parallel continuous regularly offset strip members interconnected at their corresponding oppositely offset positions by leg members.

15. A blank capable of being formed into a sun-screen comprising a sheet substantially rhomboidal in shape and having therein and at an acute angle to an edge thereof a plurality of like parallel series of parallel regularly offset overlapping slits in which the regular offset dis-

tance between slits within each series does not exceed about three-fourths the distance between corresponding slits of adjacent series, and in which the distance of overlapping between

5 slits within a series does not greatly exceed the distance between corresponding slits of adjacent series, said slitted sheet thus defining a plurality of parallel continuous regularly offset strip members interconnected at their corresponding op-

10 positely offset portions by leg members.

16. The method of forming the blank defined in claim 14 into a sun-screen which comprises successively displacing each strip member diagonally downward and backward in the bias direction

15 to force the strips into substantially parallel planes and to cause the leg members to become inclined to the strips and to the general plane of the resulting screen.
